MACHINE FOR WRAPPING FOLDED SHEETS

John A. Holmberg, Camas, Wash., assignor to
Crown Zellerbach Corporation, San Francisco,
Calif., a corporation of Nevada

Application February 15, 1947, Serial No. 728,805

4 Claims. (Cl. 93—93)

1

This invention relates to machines designed to press together and wrap bundles of folded, double folded, or interfolded sheets of paper, particularly folded sheets of toilet tissue, paper towels and the like.

An object of the present invention is to provide an improved machine which will press and compress such bundles of folded tissue or other paper as they are delivered from the folding machine and will cause a wrapper to be placed around each bundle, after which the bundles can be cut transversely into finished commercial packages of the desired uniform length.

A further object of this invention is to provide a packaging machine for folded tissue sheets which will be relatively simple in construction and simple, easy and convenient for operation by a single operator.

An additional object is to provide an improved machine of the type above indicated in which a specially arranged "squeeze bar" will operate automatically to compress each group of folded sheets into the desired bundle size to enable the wrapper to be secured around the compressed bundle with a minimum of effort and care on the part of the operator.

Another specific object is to provide a machine for compressing and wrapping folded sheets in which the operator will be required only to slide a group of folded sheets on a working surface over and past a pressure bar, and will not be obliged to pick up the group of sheets and lift them over the pressure bar in the manner customary in such machines heretofore.

In the accompanying drawings:

Fig. 1 is a top plan view of the machine;

Fig. 2 is a sectional elevation taken on line 2—2 of Fig. 1;

Fig. 3 is a fragmentary side elevation corresponding to line 3—3 of Fig. 1; and

Figs. 4, 5, 6 and 7 are incomplete, more or less diagrammatic, sectional side elevations illustrating the four stages occurring in each complete cycle of operation of the machine.

An operating table top 10 is supported at each side by a suitable standard or frame 11 and these standards 11 also serve as bearing supports for the several transversely-extending horizontal shafts hereinafter mentioned. At the front of the machine the table top 10 terminates in a chute 12 (see Fig. 2 and Figs. 4 to 7), which extends the full width of the machine and from the bottom of which the wrapped, compressed bundles of folded toilet tissue are delivered. The two side walls of the chute 12 are parallel and

2

are spaced a distance apart equal approximately to the overall desired width of the finished wrapped bundles so that the wrapped bundles can easily be pushed down the chute and delivered from the bottom end thereof.

Beyond each end of the chute 12, and on the outside of each of the standards 11, a pair of vertical guideways 13 (Fig. 3) are secured and a sliding block 14 is mounted for up and down movement at each side of the machine. Each of these blocks 14 is connected by means of a link 15 to a crank 16, and the cranks 16 are rigidly secured respectively to the two ends of a main shaft 17.

A pair of supporting posts 18, rigidly mounted on the sliding blocks 14, serve as supports for the opposite ends of a press bar or press bridge 19. This press bridge 19 is hinged to the top of one of the posts 18 (thus the left hand post as viewed in Fig. 1), and a counter balance weight 20, carried on a rod 21 secured to and extending beyond the end of the press bridge 19, enables the press bridge 19 when swung upwardly on the hinge at that end to remain in raised inoperative position until the operator brings the opposite end of the press bridge down into contact with the other post 18. The other post 18 is provided with a yoke 22 which slides over the said opposite end of the press bridge 19 and thus holds that end of the press bridge down on its post 18 in operative position when desired. Partial rotation of the shaft 17 then causes the press bridge to move downwardly while maintaining its horizontal position. The purpose of the press bridge will be explained later.

A slot 23 (Figs. 2 and 3), extends across the work table top 10. An angle iron shield 24 and a horizontal plate 25 are mounted for up and down movement within said slot 23. The plate 25 is supported on a pair of rods 26 which slide through stationary brackets 27. Interposed coil springs 28, one on each rod 26, act to hold the plate 25 normally on the same level with the work table top 10 but permit the plate to be pushed down against the force of the springs.

The angle iron shield 24, which, as shown in Figs. 2 and 3, has a vertical back wall and a horizontal top wall, is firmly attached at each end to a plunge rod 29, and the bottom ends of the plunge rods 29 are pivotally connected respectively to rocker arms 30 (Fig. 2). The rocker arms 30 are keyed to a shaft 31 near its opposite ends. An intermediate rocker arm 32, which is also keyed to shaft 31, is arranged so as to be engaged by a foot pedal lever 33 so that down-

ward pressure on the foot pedal 34 will cause downward movement of the plunge rods 29 and therewith downward movement of the angle iron shield 24 and with it downward movement of the bar 36 when the latter is positioned within the shield 24. A pair of coil springs 35 act to keep the rods 29 normally in the raised position shown in Fig. 2.

A "squeeze bar" 36 (Figs. 1 and 2), preferably of rectangular cross section, the length of which bar corresponds approximately to the width of the work table top 10 and the cross sectional dimensions of which correspond approximately to the inner dimensions of the shield 24, is pivotally connected at its ends to a pair of blocks 37 respectively. A rod 38 (Figs. 1 and 3) is slidable in each pivot block 37. A stop 39 is secured on each rod 38 on one side of the pivot block 37 and a compression spring 40 is mounted on each rod 38 between the opposite side of the block 37 and a nut 41 carried on the inner end of the rod 38. The forward or outer end of each rod 38 is connected to a crank arm 42 and the pair of crank arms 42 are keyed to the ends of a shaft 43. A sprocket wheel 44, also keyed on shaft 43, is connected by a sprocket chain 45 to a similar sprocket wheel keyed on the main drive shaft 17 (the latter mentioned sprocket wheel being shown in broken line in Fig. 3).

Thus rotation of the main drive shaft 17 produces up and down movement of the press bridge 19 and horizontal movement of the "squeeze bar" 36. A pair of guideways 46 limit the sliding movement of the "squeeze bar" 36 on the work table top 10.

A worm gear 47 (Fig. 2) keyed to the main shaft 17, is driven through the medium of a worm gear reducer (indicated at 48 in Fig. 2), and the worm gear reducer in turn is connected to a motor 49. Operation of the motor 49 is controlled by suitable manual press-button switches 50 (Fig. 1) located conveniently near the operator. A pair of limit switch elements 51 (Fig. 2), having adjustable contact members, are mounted on the worm gear 47 and are adapted to engage a cooperating limit switch element 52 which is connected to the motor 49.

The forward wall of the chute 12 extends above the level of the work table top 10, as indicated at 53 in Figs. 2, 3 and 4, and then extends horizontally forward to form a narrow elevated horizontal support 54. On this support 54 are a pair of spring members 55 (Figs. 1 and 4) which engage the forward edge of a wrapper sheet 56, the rear edge of which extends through a slot in the work table top 10 and under a hinged spring lid indicated at 57.

The operation of the device is as follows:

The sheets of folded tissue 60 (Figs. 1 and 4) are delivered to the work table top 10 from one of the well known paper cutting and folding machines commonly used. The folded sheets as delivered are pushed along on the table top 10 from right to left, as viewed in Fig. 4, until the first sheet reaches the angle iron shield 24 which will be in the position shown in Fig. 4. Preferably the machine which folds the paper and delivers it to the work table top 10 cuts a tab 61 in one of the sheets after each predetermined number of sheets, as is sometimes customary in such machines, and this tab serves as an aid to the operator in having exactly the same number of sheets formed into each bundle.

At the start of the operation of my device the shield 24 and the "squeeze bar" 36 are in the

position shown in Fig. 4. The press bridge 19 (not shown in Fig. 4) is in the raised and inoperative position previously described. The operator first places a wrapper sheet 56 in the position shown in Fig. 4. This wrapper sheet may be obtained from a pile of wrapper sheets (not shown) located conveniently below the hinged lid 57 of the table top 10, or from any other satisfactory and convenient source. When the wrapper 56 is in position the operator presses down on the foot pedal 34 (Figs. 1 and 2). This causes the shield 24 and "squeeze bar" 36 to be lowered to the position shown in Fig. 5 with the top surface of the shield 24 being on the same level as the work table top 10. While the foot pedal 34 is held down the operator reaches over and pulls the first group of folded sheets (that is, the group to the left of the marker 61 in Fig. 4), to the front of the machine into the position shown in Fig. 5. When this has been done the operator releases the foot pedal 34 which permits the shield 24 and "squeeze bar" 36 to return to the normal raised position previously referred to in Fig. 4. At the same time the operator presses a push button switch starting the motor 49. This results in slow rotation of the main drive shaft 17 and with it the shaft 43. Rotation of shaft 43 produces movement of the crank arms 42 (Fig. 2) and movement of the rods 38 and thus causes the "squeeze bar" 36 to move in a forward direction as illustrated in Fig. 6, compressing the group of folded sheets ahead of it. When the "squeeze bar" 36 has nearly reached its extreme forward compressed position one of the limit switches associated with the drive gear 47 (Fig. 2) functions to shut off the motor 49 temporarily. The operator then brings the free or raised end of the press bridge 19 down onto its supporting post 18 (Fig. 2) and slides the yoke 22 over this end of the bridge 19. When the press bridge is thus secured in place the operator pushes a press button switch to start the motor again. This second operation of the motor causes the "squeeze bar" 36 to move a slight distance further forward to its extreme forward position and to remain in this position for a moment and simultaneously causes the press bridge 19 to move downwardly on top of the compressed bundle of folded tissues, this compressed bundle being indicated at 62 in Fig. 7. As this compressed bundle of sheets 62 is pushed downwardly in the chute 12 by the press bridge 19 the wrapper 56 is pulled down with the bundle 62 as shown in Fig. 7. After slight further downward movement of the press bridge 19 the continued operation of the motor with the further rotation of the shafts 17 and 43 causes the press bridge 19 to move upwardly and causes the "squeeze bar" 36 to move rearwardly back to the starting position illustrated in Fig. 4. When these members reach their starting positions the limit switch elements associated with the drive gear 47 again stop the motor. Thereupon, the press bridge being raised, the operator folds the top flaps of the wrapper 56 over on each other and on top of the bundle 62. Adhesive is previously applied to the edge of the top flap. After this completion of the cycle of operation of the machine the operator places another wrapper in the position shown by the wrapper 56 in Fig. 4. Meanwhile the folded tissue sheets have continued to be delivered to the work table top 10 so that the sheets have again been pushed up to the rear face of the shield 24. The machine is now ready for another complete opera-

Various modifications could be made in the construction of the different parts of the simple machine which I have described and which has been very satisfactorily employed for the carrying out of my invention, and other mechanism could be designed for producing the various movements of the "squeeze bar" which constitutes an essential feature of my invention. It is not my intention to restrict my invention to the particular operating mechanism illustrated and described or to limit my invention otherwise than as set forth in the claims.

I claim:

1. In a machine for wrapping folded sheets, a working table surface for receiving the folded sheets to be wrapped, a stop element extending up above the forward portion of said working table surface, a slot extending across said working table surface, a compressing member, a shield associated with said member, said member and shield normally positioned above said slot, means for temporarily lowering said shield and member to permit a group of folded sheets to be moved forward on said working table surface past said shield and member, means for returning said shield and member to normal position, and means for moving said member forward from said shield on said working table surface from its normal position so as to enable said member to compress the folded sheets located between said member and said stop element.

2. In a machine of the character described, a working table surface for receiving folded sheets to be wrapped, a chute connected with the forward end of said working table surface, a retaining wall extending up above the forward side of said chute, a squeeze bar extending the full width of said working table surface, a slot extending across said surface, said squeeze bar normally positioned above said slot, a support for said squeeze bar in said slot, means for temporarily moving said support and said squeeze bar downwardly in said slot to permit a group of folded sheets to be moved forward on said working table surface past said squeeze bar, means for returning said support and said squeeze bar to normal position, means for sliding said squeeze bar forward on the top of said working table surface from its normal position to the rear side of said chute so as to enable said squeeze bar to compress the folded sheets located between said squeeze bar and said retaining wall, a press member adapted to press downward on a group of sheets while said group is held in compressed position by said squeeze bar and adapted to press said group down into said chute, and means associated and synchronized with said squeeze bar sliding means for moving said press member downwardly on said group while said squeeze bar is in forward position.

3. In a machine of the character described, a working table surface for receiving folded sheets to be wrapped, a chute extending downwardly from said working table surface, a stop wall extending up above the forward side of said chute,

a squeeze bar, a shield extending over a portion of said squeeze bar, said squeeze bar and said shield normally positioned above said working table surface, means for temporarily lowering said shield and with it said squeeze bar to permit a group of folded sheets to be moved forward on said working table surface past said squeeze bar and shield and then for returning said shield and squeeze bar to normal position, means for moving said squeeze bar forward from said shield on said working table surface from the normal position of said squeeze bar to the rear wall of said chute so as to enable said squeeze bar to compress the folded sheets located between said squeeze bar and said stop wall, a press member adapted to press downward on a group of sheets while said group is held in compressed position by said squeeze bar and adapted to press said group down into said chute, and means for moving said press member downwardly on said group while said squeeze bar is in forward position, whereby to push said compressed group of sheets down into said chute.

4. A machine for wrapping folded sheets comprising a working table surface for receiving folded sheets to be wrapped, a chute extending downwardly from the forward end of said working table surface, a retaining wall extending up above the forward side of said chute, a squeeze bar, a shield associated with said squeeze bar, said squeeze bar and said shield normally positioned above said working table surface, means for temporarily lowering said squeeze bar and said shield to permit a group of folded sheets to be moved forward on said working table surface past said shield and said squeeze bar, and then for returning said shield and squeeze bar to normal position, means for moving said squeeze bar forward on said working table surface from its normal position to the rear wall of said chute so as to enable said squeeze bar to compress the folded sheets located between said squeeze bar and said retaining wall, a press member adapted to press downward on a group of sheets while said group is held in compressed position by said squeeze bar and adapted to press said group down into said chute, and means associated and synchronized with said latter mentioned squeeze bar moving means for moving said press member downwardly on said group while said squeeze bar is in forward position, whereby to push said compressed group of sheets down into said chute.
